UNITED STATES PATENT OFFICE.

GEORGE H. MAXWELL, OF PHOENIX, ARIZONA.

SHOE-BOTTOM-FILLER MACHINE.

Application filed August 9, 1923. Serial No. 656,496.

To all whom it may concern:

Be it known that I, GEORGE H. MAXWELL, a citizen of the United States, and a resident of Phoenix, county of Maricopa, and State of Arizona, have invented a new and useful Shoe-Bottom-Filler Machine, of which the following is a specification.

My present invention is an improvement in and subordinate to and a continuation in part of my copending application Serial No. 633,148, now Patent No. 1,523,701, dated January 20, 1925, and likewise of the prior, but still copending application Serial No. 560,800 therein mentioned and which on October 21, 1924, became Patent No. 1,512,929.

The present improvements relate primarily to the adaptation of electricity to this type of apparatus. I have found that much of the trouble experienced in the electrically heated filler machines has been due to the presence of moisture in the chamber containing the heating element and also that much finer control of the conditioning of the filler is possible by maintaining a dry heat around the filler containing chamber and a moist heat within the filler containing chamber. Accordingly one aim of my present invention is to maintain the heating chamber dry and free of moisture, although generating the steam within it. One of the chief features of invention in my application 633,148 was the provision of a heat disseminating space or chamber formed by so positioning the heating unit below the bottom of the reservoir and work-basin of the apparatus as to give quick heating results but without localizing undue heat at any one spot or region of said bottom which would be liable to burn the filler. In other words,

40 by placing the heating unit as stated the space between said unit and said bottom constitutes a heat disseminating or unifying space to render the heat all around said bottom uniform and safe. As, however, the 45 main object of the original invention, i. e. of this entire type of machine, is to speed up the process of filling shoes with this kind of filler it is desirable to have an extra high heat, especially at the beginning when it

50 is necessary to melt the large body of filler and also heat up all the parts of the previously cold machine. For instance, when the operator starts in the morning it is desirable that he should be able to begin the actual filling of the shoe-bottoms within at

least 10 minutes (and even a shorter time if possible). This problem presents exceedingly great difficulties, bearing in mind that the material is largely cork mixed with wax tailings, rosin, starch and such like easily-charred material and that nevertheless their heat penetration is slow because of the heat insulating character of the cork. The safety means which I have provided and which permits employing an extra high-heat heating unit resides in interposing in the aforesaid disseminating space or chamber and between the heating unit and said bottom a water chamber or container covering more or less of the radiating surface of the unit. 60 This absorbs a considerable portion of the fierce heat at the start because of the water and because of the barrier provided by the water container and yet it permits a considerable portion of the radiant heat to be 65 spread throughout the disseminating space and over the entire bottom and around the basin and the reservoir. On the other hand the space directly over the heating unit which has been protected by the water chamber is brought up to its desired rapid-melting condition as quickly as the heating of the apparatus makes safe, this rapid bringing up of said area to said condition being due to the increasing heat thereat as the water 70 in the chamber becomes converted into steam. And even though at this moment the heat is intense no harm is likely because as the water became quite hot the wet vapor ascending therefrom has entered and 75 coated and permeated the mass of filler, and has therefore rendered the filler less liable to burn, followed at once by still hotter vapor and finally by true steam, it being understood that in the further running of the 80 apparatus the main melting of the filler is accomplished by the steam rather than by the dry heat. As soon as this point is reached the operator can turn off the high current, leaving the unit on medium or low 85 heat just sufficient to keep the water chamber generating steam sufficient to continue the melting and conditioning of the filler. The highly heated condition of the reservoir and basin maintains this steaming condition, 90 as the hot metal instantly converts back into steam again any drops of water or accumulation of condensation as soon as said water comes into contact with the hot metal bottom or wall. This concentration of the 95 100 105 110

source of heat and the region of effort and application, whether it be an electric unit or any other kind, at and adjacent the bottom of the work-basin and of the mass of 5 filler, is of special advantage and combines with the other features and functions to produce economy, speed, safety and convenience. My present process and combination of parts and their resulting effects in use so 10 modify each other as to permit the employment with safety of an extra strong heat (say 2000 watts, by way of illustrating my point by reference to the electric form of heater) which would have charred and 15 scorched and totally ruined the filler at once under previously existent conditions, and yet this high heat is all utilized, and safely utilized, the larger part being used in the steam and the surplus used as dry heat in 20 the air chambers around the reservoir and work-basin. To melt and condition and so maintain such a large mass of filler while being used would normally require say 8000 to 10,000 watts to produce the necessary 25 steam, but by concentrating the 2000 watts mentioned in a unit of say 10 inches diameter with the effective steam generation and application thereof confined close to it at the lower end of the mass and simultaneously all over and through said lower end where and as the filler is used and falls or disintegrates and opens up for this forced steam-penetration, the result is a quick, efficient conditioning of the filler and marked 35 economy of energy. The high, sudden or harsh heat produces forced steam delivery and rapid penetration with sufficient effectiveness all along the lower end of the mass at the several points where the jets of steam 40 are driven into the loose filler to coat each particle of filler with moisture and to keep it so coated at the very time and place where otherwise it would be charred and scorched by contact with the hot bottom plate which 45 at the same time and by the same dry and extra high heat on its under side has been brought to an extra heat. Thus both metal and filler are kept more highly heated and by the same simultaneous applications and 50 with self-insured safety than would have been previously possible, and this goes on continuously and with an expenditure of minimum energy because it is progressive in its maximum efficiency at the point or region 55 of use. The arrangement is such that both metal and filler are kept conditioned for the highest, yet safe, service. This is promoted by the loose condition of the filler and its disintegrating tendency which increases with 60 its approach to the bottom. The machine, in its complete and preferred embodiment, is so constructed that the mass is held apart in small portions which are simultaneously attacked with the steam and dry heat, the 65 apparatus holding the filler portions thus separated so that they cannot pack into a solid mass but on the contrary get increasingly loose and open and permeable toward the bottom by maintaining a considerable depth or extent of melted and conditioned 70 filler disintegrating and dropping or tending to drop and flow loosely down and forward by gravity continuously. The structure just explained whereby there is a concentration and suddenness of attack and result has considerable influence, viz., the jet-like or forced steam discharge whereby is caused the sudden formation of the slimy or starchy paste, the sudden melting of the waxy binder, the sudden formation of the 75 steam (so that at the start the bottom part of the filler is steam coated even before the metal bottom is very hot) especially in the electric machine of the present application, and the high or extra heat in its concentrated form which produces this quick steam 80 to the extent necessary and affords the waste heat or surplus left over from the steam production which surplus is simultaneously 85 and automatically used for the desired high dry heat around the reservoir and the work-basin (whose use, thus extra hot, is made safe and possible by the steam on the other side, said steam increasing with the heat). My machine and process proceed on the 90 principle of loosening the filler, or dropping, opening, freeing the particles, and disintegrating, as diametrically opposite to forcing down, compressing and compacting or 95 integrating (which has been before proposed). Further features of invention will appear in connection with the following description and all will be covered by the appended claims.

In the drawings in which I have shown 105 the preferred embodiment of my invention, Fig. 1 is a central vertical section of the machine from front to back;

Fig. 2 is a detail in top plan of the electric heating unit and its mounting; 110

Fig. 3 is a vertical sectional detail on the line 3-3, Fig. 1;

Fig. 4 is a fragmentary view in front elevation of the roll, knife block and shelf; 115

Fig. 5 is a fragmentary top plan view of the parts shown in Fig. 4.

The general construction and mode of operation of my apparatus is the same as set forth in my application Serial No. 633, 120 148. Mounted on a pedestal 1 is a base 2 having upturned inclosing sides 3 and ends 4, 5. The work-basin 6 and reservoir 7 are the same as shown in the electrical form 125 of the apparatus contained in my application aforesaid, said reservoir containing heat radiators or flues 8 and being closed by a cover 9 and divided slide doors 10, 11. At the left hand side of the work-basin is an inclined shelf 12 above which are mounted the 130

roll 13 and knife block 14, carried on supports 15, 16 preferably in the form of pipes to hold the current wires; and the heating units for the roll and knife block are in 5 the form of the well-known tubular or cartridge units one placed in the roll and one in the knife block and the wires led therefrom through the supports to a switch 17. To accommodate the height or other 10 peculiarities of different operators the supports 15, 16 are held vertically and rotatably adjustable in their bearings in the shelf 12 by set bolts 19. As it is desirable to have the entire front of the reservoir capable 15 of being quickly opened so as to permit the operator to clean out any lodged filler, I have simply connected the opposite sides of the reservoir by a small bar 20 and secured the front top edge of the radiators 20 thereto or preferably their angle iron protectors 21 are riveted or welded thereto at their front ends and at their rear ends to the rear wall of the reservoir. The slide door 10 has an overhanging upper end 22 and 25 the lower slide door or section 11 slides in fairly tight engagement with said door section 10 so that the operator may therefore readily inspect the lower portion of the apparatus by simply raising the door 11, but 30 if he wishes to disclose the entire vertical length of the radiators and the spaces between said radiators he simply continues to lift the door 11 after its upper edge has struck the flange 22 and thereby he raises 35 both doors 10 and 11 as far as desired or entirely from the apparatus. The hinged cover 9 has its handle 23 arranged to project laterally a considerable extent so as to be out of range with the escaping steam 40 when the cover is being raised.

Just below the horizontal portion 24 of the bottom of the work-basin and the reservoir I mount the water basin or steam generator 25 shown as a closed basin or 45 sealed pan whose purpose and functions have already been explained. This is located in the heat disseminating space or chamber between said bottom 24 and the radiant heating unit 26 and has an inlet 50 pipe 27 connected by a U-loop 28 to the water seal 29 for receiving water from the supply tank 30 provided with an air pipe 31 and outflow tube 32 and mounted all as shown and explained in my application 55 Serial No. 633,148. Adjacent the upper corner of the water chamber or container and steam producer 25 is a steam outlet pipe 33 connected with a distributor pipe 34 and individual pipes 35 discharging respectively 60 into the reservoir 7, preferably by entering the flues 8 and held in the inclined portion 36 of the bottom by a tight joint formed in any suitable manner as by nuts 37. By this means the steam is forced or 65 delivered under pressure into the mass. It is formed suddenly in the confined container or closed basin and carries the heat immediately into and throughout the mass of filler at the desired plurality of points. In order to speed up the process and loosen 70 down the filler which is normally slowly penetrative by heat and yet is liable to burn at high heat, the mass is held apart at a plurality of places or provided with a plurality of openings extending vertically 75 in the mass for simultaneously receiving a melting heat throughout their vertical walls. This starts the crumbling or dropping tendency simultaneously throughout practically the entire mass of the filler in spite of the fact that it is not easily penetrated by heat, said dropping or falling and loosening taking place most rapidly adjacent the bottom where the steam has direct impact against and access to the filler with 80 the combined melting and protective effect already explained. Cross reference is also made to my Patent No. 1,512,230 granted October 21, 1924 on copending application Serial Number 633,148 filed April 19, 1923, 85 in which the same forced or pressure-driven nozzle-jets of steam-delivery into the reservoir and contained filler is shown but in connection with a different species of steam producer. Both that species and the present apparatus are, however, radically distinguished from my original application (Patent 1,512,229 before mentioned) in which the steam had no forced or nozzle-jet delivery, but rather was delivered from 90 the wide open pan or basin-like generator as a cloud or vapor through the unrestricted foraminous bottom and said bottom had the moisture or wet cloud of steam spread co-extensively over its underside and upper 95 side. The unit 26 as herein shown is of the circular radiant type and therefore the steam producer or water chamber 25 is preferably circular and is preferably somewhat smaller than the electric heating unit 100 in order that the latter may have a portion exposed beyond the protection of the water chamber for facilitating rapid heating at the start. The heating unit is shown as mounted on a stand or support 38 and carried by a frame or clamping band 39 held in proper clamping adjustment by a bolt 40 and secured at its ends 41 to a door or closing plate 42 on which is mounted the switch 43 and switch box (not shown). The 105 switch is preferably of the usual three-heat type. Considerable trouble has been experienced with previous electrically heated filler machines as heretofore used for the kind of filler of Patent No. 861,555, July 30, 1907 and after much investigation and experimenting I have discovered that the greater part of this trouble has been due to the burning off or disintegrating of the 110 insulation on the electric wires in the pres- 115

120
125
130

ence of continuous intense heat. Accordingly, I have devised the construction shown and just explained which permits the bringing out of the bare wires from the radiant heating unit directly into the switch without any insulation which could burn off or injure. Furthermore, in case of any injury to the heating unit all that is necessary is to loosen the plate 42 and thereby pull out the entire heating unit and its connections. A smaller plate or door 44 is provided at the rear end to permit of ready access for replacement or repair of any of the contained water and steam connections. Steam is always used in the filler for speed and safety, but dry heat from the dry-heat chamber beneath may be used for the radiators.

In use, the operator fills the reservoir with filler and then turns on the switch 43 to high heat. The automatic water supply 27-32 keeps the water chamber properly filled with water. This acts to protect the bottom 24, 36 against localized burning directly over the unit 26 in the heat disseminating space or chamber between said unit and bottom. As the apparatus gets heated and the filler begins to melt, the water in the chamber or container 25 begins to vaporize and passes out through the pipes 33, 34, 35 into the reservoir and preferably into the radiators or flues 8 and into the filler contained in the spaces around or between said radiators. This construction constitutes a safety means of protective provision which permits considerable accelerated speed of starting and of operation. The water in the chamber 25 is first vapor and then quickly gets into the condition of steam and then hot steam, but is never intended to become really dry steam. Before this latter point might be reached the operator turns down the switch 43 from high to medium and finally to low heat. The percolating steam keeps the filler particles in the reservoir coated with sufficient protecting moisture to prevent accidental burning when the filler later falls on the hot bottom 24. Also some condensation reaches said hot bottom which converts it back into steam and there is always a tendency to provide a permeating moist heat in all the filler wherever it may be in the apparatus. This feature of my invention is important in facilitating the rapidity and safety upon which I have already placed special emphasis. The maintenance of steam heat above the bottom in and throughout the filler mass and particularly wherever the filler contacts with the hot bottom or the walls of the reservoir and radiators insures that the sensitive filler is not burned or overheated and the high heat of the bottom and walls maintains the steam condition by preventing any accumulation

of water and hence insures the filler against saturation or water-injury. The steam enters as steam and my aim is to maintain it as steam, or at least as such a thin, inappreciable film of moisture on the particles that the latter are never wet in the sense of being saturated or surrounded with water. The bottom may be kept hot by any means as for instance as in my applications Serial Nos. 560,800 and 633,148, or preferably as in the present species where it is kept hot by dry heat. In other words I am able to keep up high speed of operation by maintaining the metal at such a heat that it converts condensation, if any, back into steam. And this accomplishes the further purpose of keeping the filler just right by preventing the filler from getting too wet to lay and losing its active stickiness. Steam is much more penetrative than dry heat alone, and hence the combination of the two, or their concerted action, whereby the steam drives along the dry heat, hastens the melting. The dry heat is reinforced by the wet steam heat which facilitates the heat penetration of the granular mass, helps to separate it rapidly into the desired loosely flowing condition which is specially adapted for the required spreading or laying within the shoe-bottom and also protects it against burning so that the high heat mentioned is safe which could not otherwise be used. The branching pipes 33, 34, 35 or equivalent means for conveying jets of steam simultaneously to the loose and loosening area or region of the bottom of the mass of filler is very important as thereby the filler particles at all points of possible contact with the metal bottom 24 are rendered burn-proof simultaneously with the raising of said bottom 24 to its burning heat. Without this plurality of jets of penetrating moisture at and throughout said region it would not be possible to use the sudden and intense, harsh heat and the speed and quick efficiency already explained would not result. But by concentrating the high-heat and severe wattage of the unit 26 directly under the protecting and disseminating steam generator 25 relatively close to the metal bottom and delivering the steam at short range and a sufficient plurality of places here and there in the lower end of the mass of filler, the filler stratum on and just above the metal bottom is melted, moistened and rendered safe all at the same moment and automatically by the same source (and hence the same acceleration or speed of heating) as the metal bottom. The hotter the metal gets the faster the steam is discharged all over the top side of it, that is to say, in protecting and melting relation to the otherwise burnable filler particles on and near said hot metal bottom. The open, loose and

- disintegrating or segregating condition of the filler and opportunity therefore for opening down and self-loosening because of the free gravity flow, has a most favorable influence in aid of the speed, safety and economy secured. This so facilitates the steam penetration, quick softening and rapid use that a more powerful high-heat unit is possible, capable of furnishing with safety 10 at the one point of concentration all the heat necessary for the sudden and copious steam production required and for the dry heat to maintain the work-basin and elsewhere in the condition of highest efficiency. 15 This tends to further economy as the production of the steam necessarily wastes heat or leaves a surplus from the steam production, and my arrangement utilizes this waste or surplus with safety. If any lodged 20 filler between the radiators or flues 8 needs attention the operator raises the lower section 11 of the door or if necessary continues to raise said section until it overlaps section 10 and strikes against the flange 22 and 25 thereby raises the section 10 along with the section 11 removing the two entirely from the apparatus if desired. If the roll 13 and knife block 14 are too low or too high or not at the right angle they are adjusted 30 to suit the operator by means of the set screw 19. As the operator fills the shoe-bottom with a hot knife from the knife block 14 he quickly levels and condenses the filler in the shoe-bottom by pressure against 35 the roll 13 and any surplus filler that drops on the hot inclined shelf 12 is made highly fluid by contact and flows at once back into the work-basin.
- Although my apparatus is subordinate in 40 some respects to the claims of previous applications and relates to improvements, in others it contains dominating claims (certain of which have been divided out from the application Serial No. 633,148), it will be evident to those skilled in the art that 45 many variations and substitutions of embodiments are contemplated within the spirit and scope of the following claims which further define my invention:
- 50 1. In a machine of the kind described, a filler supply reservoir, a heater spaced below said reservoir a short distance sufficient for heating the apparatus speedily at a high heat without danger of burning the filler, a closed water chamber and steam producer between said heater and the bottom of the reservoir, and steam conveying means for conveying the steam from said chamber into the reservoir.
- 55 2. In a machine of the kind described, the combination with a filler softening reservoir adapted to handle shoe-bottom filler which prior to use is normally self-sustaining but sluggishly fluid under moderate heat, of a heating unit or source of heat beneath 60
- said reservoir, a closed water chamber and steam producer in protecting relation between said unit and the bottom of said reservoir, and means permitting the discharge of steam from said producer into said reservoir at a plurality of separated places through said bottom. 70
3. In a machine of the kind described, the combination with a filler softening reservoir adapted to handle shoe-bottom filler which prior to use is normally self-sustaining but sluggishly fluid under moderate heat, of a heating unit or source of heat beneath said reservoir, a closed water chamber and steam producer in protecting relation between said unit and the bottom of said reservoir, and means for discharging steam from said producer through said bottom into the filler in the reservoir in the form of jets of steam delivering at a plurality of separated places. 75
4. In a machine of the kind described, a filler-supply reservoir, a removable electric heater spaced below said reservoir a short distance sufficient for heating the apparatus speedily at a high heat without danger of burning the filler, a closed water chamber and steam producer between said heater and the bottom of the reservoir, and steam conveying means for conveying the steam from said chamber into the reservoir. 80
5. In a machine of the kind described, a filler-supply reservoir, a heater spaced below said reservoir a short distance sufficient for heating the apparatus speedily at a high heat without danger of burning the filler, a closed water chamber and steam producer between said heater and the bottom of the reservoir, an automatic water supply for maintaining said chamber supplied with water, and steam conveying means for conveying the steam from said chamber into the reservoir. 85
6. In a machine of the kind described, a filler-supply reservoir, an enclosure beneath said reservoir, and safety heating means within said enclosure, comprising a broad, shallow closed chamber for water to be converted into steam, a heater directly under said chamber, water connections to said chamber, and steam connections from said chamber to the reservoir. 90
7. In a machine of the kind described, a filler-supply reservoir, an upstanding radiator flue in said reservoir, an enclosure beneath said reservoir, and safety heating means within said enclosure comprising a broad, shallow closed chamber for water to be converted into steam, a heater directly under said chamber, water connections to said chamber, and steam connections from said chamber to the flue and thence into the reservoir. 95
8. In a machine of the kind described, a filler supply reservoir having a plurality of hollow melting-flues extending within it in 100
- 105
- 110
- 115
- 120
- 125
- 130

position to introduce a melting heat at a plurality of regions within the mass of filler contained within the reservoir, means for introducing steam into the reservoir 5 from outside the reservoir, and means for preventing the escape of steam or filler at the steam inlet.

9. In a machine of the kind described, a filler supply reservoir having a plurality of 10 flues extending within the same, heating means below said reservoir and flues, and a steam pipe extending into each flue for supplying jets of steam into said flues and thence into the filler mass surrounding the 15 flues, all constructed and arranged to maintain a dry heat below said reservoir and flues and a moist heat in said reservoir and flues.

10. In a machine of the kind described, a 20 filler supply reservoir and work-basin, a heat radiator and steam flue extending within said reservoir for hastening the melting and conditioning of the filler, means for providing dry heat below and around said 25 apparatus for melting and maintaining the filler in workable condition in said work-basin, and means for supplying steam to said radiator and steam flue and thence into the filler in the reservoir for conditioning the filler surrounding said radiator and 30 steam flue, the aforesaid construction being arranged to maintain dry heat below said supply reservoir and work-basin and moist heat in said reservoir.

11. In a shoe-bottom filling machine for 35 the rapid handling with high heat of a heat responsive, sticky filler which is normally slowly penetrative by heat and liable to burn at high heat, the combination with a filler supply reservoir adapted to the rapid 40 handling of a mass of said filler and to maintain the filler supported on and above the bottom of said reservoir in a loose, open, non-compressed and non-compacted condition, of heating means arranged to maintain 45 two kinds of heat on the opposite sides of said bottom of said reservoir, namely, a dry heat immediately beneath and in heating contact with said bottom and a wet protective heat immediately above and in 50 protective contact with said bottom and in the adjacent filler mass, all constructed and arranged for safety at high heat and to cause the filler to loosen bottomward and tend to disintegrate downward as distinguished from solidifying and compacting at the bottom.

12. In a shoe-bottom filling machine for 55 the rapid handling with high heat of a heat responsive, sticky filler which is normally slowly penetrative by heat and liable to burn at high heat, the combination with a filler supply reservoir adapted to the rapid handling of a mass of said filler and to maintain the filler in a loose, open, non-compressed and non-compacted condition, of

heating means cooperative with said reservoir for enveloping said mass and also at the same time sub-divisions or portions of the mass with heat and moisture in order to reduce the filler mass rapidly and with 70 safety to a semi-fluid or working condition and arranged to maintain two kinds of heat on the opposite sides of the bottom of said reservoir, namely, a dry heat beneath and immediately against said bottom where it supports the mass of filler and a wet protective heat immediately above and in protective contact with said bottom and in the adjacent filler mass, all constructed and arranged for safety at high heat and to cause 75 the filler to loosen bottomward and tend to disintegrate downward as distinguished from solidifying and compacting at the bottom.

13. In a shoe-bottom filling machine for 80 the rapid handling with high heat of a heat responsive, sticky filler which is normally slowly penetrative by heat and liable to burn at high heat, the combination with a 85 filler supply reservoir arranged to hold the filler mass parted with a plurality of openings extending vertically in the mass for simultaneously receiving a melting heat throughout their vertical walls, said reservoir being adapted to hold and deliver filler 90 of said character in a loose, open, non-compressed and non-compacted condition, of a heating unit or source of heat arranged to maintain a dry high heat beneath said reservoir, and steam supplying means to introduce steam simultaneously into said several 95 parted portions of the mass of filler in the reservoir.

14. In a shoe-bottom filling machine for 100 the rapid handling of a heat responsive, sticky filler which is normally slowly penetrative by heat and liable to burn at high heat, the combination with a filler supply reservoir adapted to hold and deliver filler 105 of said character in a loose, open, non-compressed, and non-compacted condition, of a heating unit or source of heat arranged to maintain a dry heat beneath said reservoir, and steam supplying means to introduce steam to a melting extent into the mass of 110 filler in the reservoir simultaneously at a plurality of places and arranged to promote a loosening, opening and dropping tendency 115 in the bottom part of the filler mass.

15. In a shoe-bottom filling machine for 120 the rapid handling of a heat responsive, sticky filler which is normally slowly penetrative by heat and liable to burn at high heat, the combination with a filler supply 125 reservoir adapted to hold and deliver filler of said character in a loose, open, non-compressed, and non-compacted condition, of heating means for softening said filler including a chamber and a plurality of steam pipes extending from said chamber through 130

- the wall of the reservoir with a tight joint for delivering moist heat into the filler mass at a corresponding plurality of points while excluding the moisture from said chamber.
- 5 16. In a shoe-bottom filling machine for the rapid handling of a heat responsive, sticky filler which is normally slowly penetrative by heat and liable to burn at high heat, the combination with a filler supply reservoir adapted to hold and deliver filler of said character in a loose, open, non-compressed, and non-compacted condition, of a heating unit or source of heat for softening the filler in said reservoir, including a closed
- 10 15 steam producer under the influence of said unit and a plurality of branches from said steam producer extending with a tight joint through the wall of the reservoir for delivering steam into the filler mass at a corresponding plurality of points.
- 16 17. In a shoe-bottom filling machine for the rapid handling of a heat responsive, sticky filler which is normally slowly penetrative by heat and liable to burn at high heat, the combination with a filler supply reservoir adapted to hold and deliver filler of said character in a loose, open, non-compressed, and non-compacted condition, of a dry heat chamber and heating means below
- 20 25 30 said reservoir, and wet steam heating means within said chamber to deliver moist heat into the filler to facilitate the heat penetration of the loose filler mass, all arranged to promote the loosening of the filler and flowing condition thereof more actively at the bottom and delivery end of the filler mass and to protect the filler against injury by the dry heat, the aforesaid heating portion of the apparatus including controlling means
- 35 40 45 for so limiting and balancing the dry and steam heat as to maintain the sticky mass in a fluffy, light, high state of looseness without water saturation or injury to its stickiness for spreading and laying within the shoe-bottom.
18. In a shoe-bottom filling machine for the rapid handling of a heat responsive, sticky filler which is normally slowly penetrative by heat and liable to burn at high heat, the combination with a filler supply reservoir adapted to hold and deliver filler of said character in a loose, open, non-compressed, and non-compacted condition, of a dry heat chamber and heating means below
- 50 55 60 65 said reservoir having capacity in excess of the safety limits of said kind of filler in normal condition, and means for introducing steam within the filler to a protective extent guarding the filler against said excess dry heat, and controlling means for controlling and balancing said two heats and arranged to insure that the dry heat on the one hand is held in check by the moisture from burning the filler and on the other hand the accumulation of water of condensation from the steam is prevented by the dry heat.
- 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 tion, around the work-basin for maintaining the latter hot.

22. In a shoe-bottom filling machine for the rapid handling of granular, heat-sensitive, sticky shoe-bottom filler, meltable at low heat and then quick setting when allowed to cool in a shoe-bottom, a reservoir adapted to hold and deliver filler of said character in a loose, open, non-compacted 10 and non-compacted condition, a hot work-basin for receiving the softened filler from the reservoir in said condition for application to the shoe-bottom, and concentrated heating means located below said basin and 15 reservoir and arranged for forced delivery of moist heat under pressure into the reservoir and through the filler and delivery of dry heat around said basin.

23. In a machine of the kind described, a 20 filler-supply reservoir, an enclosure beneath it, and safety heating means within said enclosure, comprising a broad, shallow closed chamber for water to be converted into steam, an electric heater directly under said 25 chamber, water connections to said chamber, and steam connections from said chamber to the reservoir, said enclosure having a removable portion of its front wall secured to said electric heater and provided with 30 a switch for the latter and having a portion of its wall adjacent said water chamber and connections also removable.

24. In a machine of the kind described, a 35 filler-supply reservoir and work-basin, a plurality of upstanding radiators and flues in said reservoir affording intervening filler receiving spaces between them open at the front of the reservoir from the bottom up, closing means for said open front adjustable 40 to open the said front as desired, and heating means for said reservoir and basin including means for providing moisture within the filler and melting heat in the flues and beneath the reservoir and basin.

45 25. In a machine of the kind described, a filler-supply reservoir and work-basin, a plurality of upstanding radiators and flues in said reservoir affording intervening filler receiving spaces between them open at the 50 front of the reservoir from the bottom up, closing means including a two-part door for said open front having an upper part to give the operator free access to the upper front interior of the reservoir and a lower vertically 55 movable part extending down into the work-basin and normally closing into the filler mass to hold the heat back within the reservoir, and heating means for said reservoir and basin including means for providing moisture within the filler and melting heat in the flues and beneath the reservoir and basin.

26. In a machine of the kind described, a 60 filler-supply reservoir and work-basin, a plurality of upstanding radiators and flues

in said reservoir affording intervening filler receiving spaces between them open at the front of the reservoir from the bottom up, closing means including a two-part slide door for said open front adjustable to open the said front as desired, the top part of the slide door having a part in position to be engaged by the bottom part of the slide door so that when the bottom part has been raised into said engagement 70 both parts will then move together in further upward opening movement, and heating means for said reservoir and basin including means for providing moisture within the filler and melting heat in the flues 75 and beneath the reservoir and basin.

27. In a machine of the kind described, a filler-supply reservoir and work-basin, a plurality of upstanding radiators and flues in said reservoir affording intervening filler 80 receiving spaces between them open at the front of the reservoir from the bottom up, a supporting bar across the front of the reservoir to which the flues are held at their front ends, closing means for said open front adjustable to open the said front as desired, and heating means for said reservoir and basin including means for providing moisture within the filler and melting heat in the flues and beneath the 85 reservoir and basin.

28. In a machine of the kind described, a filler-supply reservoir and work-basin, a plurality of upstanding radiators and flues in said reservoir affording intervening filler 90 receiving spaces between them open at the front of the reservoir from the bottom up, a cover hinged to the top of said reservoir having a handle projecting freely beyond the reservoir at the extreme end of the free 95 swinging edge remote from the hinged edge, closing means for said open front adjustable to open the said front as desired, and heating means for said reservoir and basin including means for providing moisture within the filler and melting heat in the flues and beneath the reservoir and basin.

29. In a machine of the kind described, a 100 filler-supply reservoir, a work-basin in position to receive filler therefrom by gravity, and a laying roll mounted in front of said reservoir and above said basin at one side thereof, including means for adjusting 105 said roll vertically.

30. In a machine of the kind described, a 110 filler-supply reservoir, a work-basin in position to receive filler therefrom by gravity, and a laying roll and knife block mounted 115 in front of said reservoir and above said basin at one side thereof, including means for adjusting said roll and knife block vertically.

31. In a machine of the kind described, a 120 filler-supply reservoir, a work-basin in po- 125

sition to receive filler from the lower end thereof, a laying roll mounted in front of said reservoir and above one side of the basin, and a knife block back of said roll and adjustable angularly with reference to the roll.

32. In a machine of the kind described, a filler-supply reservoir, a work-basin in po-

sition to receive filler from the lower end thereof, a laying roll mounted in front of said reservoir and above one side of the basin, and a knife block back of said roll, said roll and block being relatively adjustable vertically and also horizontally.

GEORGE H. MAXWELL.
